O. J. KUENHOLD

WATER HEATER CASING

Filed August 19, 1926

Inventor
Otto John Kuenhold
by *Hannif & Hannif 1926*

UNITED STATES PATENT OFFICE.

OTTO JOHN KUENHOLD, OF CLEVELAND, OHIO, ASSIGNOR TO THE DUNHAM COMPANY,
OF BEREAL, OHIO, A CORPORATION OF OHIO.

DESIGN FOR A WATER-HEATER CASING.

Application filed August 19, 1926. Serial No. 18,781. Term of patent $3\frac{1}{2}$ years.

To all whom it may concern:

Be it known that I, OTTO JOHN KUENHOLD, a citizen of the United States, residing at Cleveland, in the county of Cuyahoga and State of Ohio, have invented a new, original, and ornamental Design for Water-Heater Casings, of which the following is a specification, reference being had to the accompanying drawing, forming part thereof.

The figure shows a perspective view of the water heater casing.

I claim:

The ornamental design for a water heater casing substantially as shown.

OTTO JOHN KUENHOLD.
